RECEIVING APPARATUS FOR COMMUNICATION SYSTEMS

Willard P. Place, Wilkinsburg, Pa., assignor to
The Union Switch & Signal Company, Swiss-
vale, Pa., a corporation of Pennsylvania

Application May 17, 1934, Serial No. 726,130

8 Claims. (Cl. 246—8)

My invention relates to receiving apparatus for communication systems, and particularly to receiving apparatus for telephone communication with vehicles in motion as, for example, a rail-
5 way train.

I will describe one form of apparatus embodying my invention, and will then point out the novel features thereof in claims.

Communication systems have been proposed for 10 telephoning between a wayside station and a train, or between two different trains, or between two spaced locations on the same train, by transmitting from one location to the other a carrier current modulated with voice frequencies or else 15 suppressing the carrier and transmitting a side band of such modulated current. Such systems preferably utilize the traffic rails as the communication channel, the current being supplied to the traffic rails at the sending location by 20 coupling the sending transmitter with the traffic rails. The current flows in the traffic rails in either or both directions from the point at which it is supplied to the rails and returns through the ground. It has been found that a line wire 25 such, for example, as a line wire commonly used in telegraph work, through its distributed capacity with the earth and with the traffic rails also serves as a path for such current. It would be helpful, therefore, to be able to receive current 30 aboard a train from the line wires paralleling the traffic rails. It is not convenient, however, to do this altogether since there are places along a railway where there are no line wires present and where it would not be convenient to 35 install a paralleling line wire. A feature of my present invention is the provision of receiving apparatus for communication systems of the type referred to wherewith signaling current supplied to the traffic rails at one location will be effectively received aboard a train either from the 40 traffic rails or from line wires paralleling the traffic rails or from both. The separate currents picked up from these two channels are independently filtered, amplified and detected and then 45 combined for actuating a signaling device.

The receiving apparatus for railway telephone systems is preferably in circuit at all times ready to receive a message from the remote point and preferably includes a loudspeaker, with the result 50 that earth currents or stray magnetic fields picked up during the non-transmitting period of the system produce a noise in the loud-speaker that sometimes becomes very annoying, especially since high gain amplifiers are employed. During 55 the telephoning period such unwanted energy

when picked up may render the reception of speech unsatisfactory and unintelligible. It has been found that the ratio between signal and noise in the line wires paralleling a railway track is often much better than the ratio between 5 signal and noise as found in the traffic rails. On the other hand, there may be times when there is more noise in the line wires than in the track. A further feature of my invention is the provision of receiving apparatus for such telephone systems 10 that will automatically select the better of two channels in accordance with the noise existing on the channels. That is, if the amount of noise received over one channel during non-transmitting period is small compared to the amount of 15 noise received over the other channel, the sensitivity of the high frequency amplifier for the channel having little noise is automatically adjusted at relatively high gain while the sensitivity of the high frequency amplifier for the channel having 20 a large amount of noise is automatically adjusted at relatively low gain. Then, when conversation is established, the telephone current received over the channel having little noise will be amplified at high gain while the telephone 25 current received over the channel having a large amount of noise will be amplified at relatively low gain and the unwanted noise current will be amplified but little. The amplification of the telephone currents received from the two channels 30 will be also kept down to a level where the combination of the two after detection will not produce a signal that is objectionable.

In explorations along railway tracks, I have 35 found that a considerable phase difference between the telephone current picked up from the traffic rails and that picked up from the paralleling line wires may exist, so that, the phase of the two currents received aboard a train may be such as would cause these currents to cancel 40 each other. A still further feature of my invention is the provision of receiving apparatus wherewith carrier telephone current received over two independent channels may be combined with little 45 loss in effectiveness on the signaling device, notwithstanding a considerable phase difference between the two currents as picked up may exist. Other features and advantages of my invention will appear as the specification progresses.

A better understanding of my invention may 50 be had from the accompanying drawing which is a diagrammatic view of one form of receiving apparatus embodying my invention. In the drawing, 3 and 4 designate inductor coils mounted on a railway train in inductive relation with 55

the traffic rails 1 and 1^a respectively. This receiver 3-4 may be mounted on any desired vehicle of the train and will be referred to in the following description as being mounted on the 5 caboose of a freight train in order to clarify the description. The outside terminals of the receiver 3-4 are connected over wires 5 and 6 with the input of a band-pass filter BPF, the two 10 portions or coils 3 and 4 being connected in series and arranged that voltages induced therein by current flowing in the same direction in the two rails are additive. Wires 7 and 8 connect the output side of the band-pass filter BPF with the input circuit of a high frequency amplifier 15 designated as a whole by the reference character HFA. To aid in the understanding of my invention I shall assume in the present description that a carrier frequency current of 8,000 cycles per second is modulated by the voice frequencies and that carrier suppressed transmission is employed, the upper side-band being transmitted. Under these conditions the band-pass filter BPF may be any one of the well-known types for such filters, which is so proportioned and adjusted as to pass a band of frequencies extending from 8,500 to 10,500 cycles per second, the voice frequencies being taken as extending from 500 to 2,500 cycles. It follows that frequencies within such upper side-band 20 range picked up from the traffic rails will be passed to the input of the high frequency amplifier with very little attenuation while frequencies outside of such range will be substantially suppressed.

35 The high frequency amplifier HFA may be of any of the several types well-known to the art and may consist of one or more stages of amplification as desired. The type of this amplifier forms no part of my invention, and it will be described only sufficiently to point out its relationship with my invention. As here illustrated, this high frequency amplifier consists of several stages of amplification the final stage of which includes an electron tube 9 while the stages 40 ahead of the final stage are shown conventionally only at 10. It will be understood that these stages ahead of the final stage each preferably includes an electron tube and affiliated circuits similar to that about to be described for the tube 45 9. The tube 9 is preferably a tetrode having an indirectly heated cathode 11, a plate 12, a screen grid 13 and a control grid 14. The control grid circuit for the tube 9 is inductively coupled with the output circuit of the stage ahead through 50 the medium of a transformer T¹, the primary winding 14 of which is included in the output circuit of that stage. The secondary winding 15 of the transformer T¹ has one terminal connected with the control grid 14 and its other 55 terminal connected with the cathode 11 through a biasing unit 16. The control grid 14 is also connected with an automatic volume control device to be described hereinafter. The plate 12 of the tube 9 is provided with a circuit that includes the primary winding 17 of a transformer T² and a source of current here shown as a battery 18 as will be understood by an inspection 60 of the drawing. The screen grid 13 of the tube 9 is connected with an intermediate point of the battery 18 over a wire 19, the filament of the tube is heated by a battery 20 and the cathode element 11 is connected with a ground electrode 45. Consequently, side-band frequencies picked 65 up from the traffic rails and passed by the filter BPF will be successively amplified at the differ-

ent stages of the amplifier HFA, will be reproduced in the primary winding 17 of the transformer T² greatly increased in amplitude and will, in turn, induce an electromotive force of corresponding frequencies in the secondary 5 windings 21 and 22 of the transformer T².

The electromotive force induced in the secondary winding 21 of the transformer T² is applied to the input of a detector or demodulator DM, the output of which is further amplified for operating a signaling device. As here shown the opposite terminals of the secondary winding 21 are connected with the input of the demodulator DM over the wires 23 and 24, and the output of the demodulator DM is connected with a primary winding 25 of a transformer T³ over wires 77 and 78. The demodulator DM may be any one of several types as desired, and as its specific type forms no part of my invention it is shown conventionally for the sake of simplicity. 20 It is deemed sufficient for this application to say that the upper side-band frequencies extending from 8,500 to 10,500 cycles per second applied to the input of the demodulator are combined with a local carrier and demodulated causing to appear in its output circuit the voice frequencies extending from 500 to 2,500 cycles. The manner of utilizing the voice frequency current supplied to primary winding 25 of transformer T³ from the demodulator DM will be fully described here- 25 in after.

The electromotive force induced in the secondary winding 22 of the transformer T² is utilized for automatically adjusting the gain of the high frequency amplifier through the medium of 35 an automatic volume control device AVC. The opposite terminals of the secondary winding 22 are connected with the input terminals of a full-wave rectifier 28 included in the automatic volume control device AVC. The output terminals 40 of the rectifier 28 are connected across a capacitance 30 and a resistor 29 in parallel which are also included in the device AVC. It follows that that portion of the amplified side-band passed to the secondary winding 22 is rectified and the 45 capacitance 30 is charged at a potential substantially equal to the peak value of the voltage induced in the secondary winding 22, the polarity of the rectifier 28 and capacitance 30 being as indicated by the plus and minus signs located 50 on the drawing.

The potential build up on the capacitance 30 is applied to the grids of the electron tubes of the different stages of the amplifier HFA for controlling the sensitivity of the respective tubes. 55 As here shown the positive terminal of the automatic volume control device AVC is connected with a ground electrode 44 over wire 49, thence through a master volume control device MVC in a manner to be more fully described hereinafter 60 and wire 13. Referring to the tube 9 of the final stage of the amplifier HFA, a grid leak consisting of two resistors 31 and 32 in series is provided and its terminal remote from the grid 14 is connected with the negative terminal of the automatic volume control device AVC over wire 33. A condenser 34 is connected between the mid-terminal of the resistors 31 and 32 and the terminal of the grid bias unit 16 remote from the cathode 11, and a condenser 35 may be inserted between this cathode connection and the wire 19 leading to the screen grid 13 for stabilizing the circuit. Recalling that the cathode 11 is connected with the ground electrode 45, it is clear that the negative bias voltage of the grid 14 70 75

is governed not only by the normal biasing unit 16 but, also by the potential built up on the capacitance 30 of the automatic volume control device AVC. The negative terminal of the automatic volume control device AVC is also connected with the control grids of the tubes included in the other stages of the amplifier HFA over the wires 33 and 36 as indicated on the drawing. Hence, the negative grid bias of each tube of the different stages of the amplifier HFA is adjusted according to the output of the amplifier.

To sum up, when current is applied to the input circuit of the amplifier HFA and an electro-motive force is induced in the secondary winding 22 of the transformer T², this alternating electromotive force is rectified and a potential is created on the capacitance 30 which potential is applied to the grids of the electron tubes of each of the stages of the amplifier in such a manner that the negative potential of the grid with respect to the cathode is varied. For example, the parts are so proportioned and adjusted that the tube 9 will be operating at substantially maximum sensitivity at the normal negative grid bias and will continue to operate at substantially the same sensitivity until the potential applied through the automatic volume control device becomes greater than that produced by the desired energy level of the signaling current. When the output of the amplifier increases above the desired signal level, the negative bias applied to the grid of the tube 9 will rapidly decrease the sensitivity of the tube with the result that unwanted noise currents having an energy level greater than that of the usual signaling current will be amplified at the tube 9 little or none. The automatic volume control device AVC being also connected with the input circuit of the stages ahead of the tube 9 as pointed out hereinbefore, the gain at each stage of the amplifier will be adjusted in a like manner in response to unwanted currents above the desired level.

When the output of the amplifier HFA remains substantially constant, a balance is quickly established and the only power taken by the automatic volume control device is that substantially negligible amount necessary to maintain the charge on the capacitance 30. Upon an increase in the output of the amplifier the charge of the capacitance 30 will be correspondingly increased and the negative grid bias applied to the tubes of the amplifier will be also increased. The change in the amplification effected by this increase in the negative bias upon the different tubes will depend upon the magnitude of the output and in a lesser manner upon the normal grid bias. As there is nothing in the circuit to cause any appreciable delay the desensitizing, of whatever magnitude, will occur relatively rapid. Upon a decrease in the output of the amplifier the potential built up on the capacitance 30 will leak off through the resistor 29 and a corresponding change will be effected upon the negative grid bias of the tubes to restore the sensitivity of the amplifier. The capacitance and resistor of the automatic control device are preferably made such that the restoring of the sensitivity of the amplifier will be relatively slow. Consequently, the automatic volume control device will be rapid enough to desensitize the amplifier in the event of sudden unwanted noise currents and will be slow enough in restoring the sensitivity of the amplifier that short conversations will not be affected thereby. It is to be

seen, therefore, that the gain of the amplifier HFA will be automatically modified in accordance with its output voltage, which, in turn is applied to the demodulator, and large voltages due to earth currents or stray magnetic fields will have their effect upon the demodulator DM suppressed.

37 is an inductor coil mounted on the caboose at any convenient point and preferably at the top of the vehicle. This inductor is preferably one of relatively large cross section and placed so that its axis is vertical causing it to be in inductive relation with a line wire paralleling the traffic rails such, for example, as the wire 2. That is to say, the inductor or receiver 37 is responsive to current flowing in the line wires and to a lesser extent to currents flowing in other conductors paralleling the traffic rails but will not respond to current flowing in the traffic rails on which the train is running. The opposite terminals of the receiver 37 are connected with the input of a band-pass filter BPF over wires 38 and 39. This band-pass filter is identical to the filter associated with the receiver 3-4 and has its output connected with the input circuit of a second high frequency amplifier HFA¹ also mounted in the caboose and which is preferably identical in structure to the high frequency amplifier HFA. The final stage of the amplifier HFA¹ includes a tetrode tube 40 which is provided with plate and grid circuits similar to the circuits described for the tube 9, and it is thought unnecessary to repeat the description. Suffice it to say that frequencies of the range of 8,500 to 10,500 cycles picked up by the receiver 37 and passed by the associated filter BPF will be successively amplified at the different stages of the amplifier HFA¹ and will induce electromotive forces in the secondary windings 41 and 42 of a transformer T⁴, the primary winding 43 of which is included in the plate circuit of the tube 40. The electromotive force induced in the secondary winding 41 of the transformer T⁴ is passed to the input of a demodulator DM¹ preferably similar to the demodulator DM and hence the current supplied by the secondary winding 41 is demodulated and corresponding voice frequencies are caused to appear in the output of the demodulator DM¹ which includes a primary winding 57 of the transformer T³, the connection being over wires 55 and 56.

The electromotive force induced in the secondary winding 42 of the transformer T⁴ is applied to the input terminals of a rectifier 46 included in an automatic volume control device AVC¹, the output terminals of the rectifier 46 being connected across a capacitance 48 and a resistor 47 in parallel with the result that the capacitance 48 is charged at a potential substantially equal to the peak value of the electromotive force induced in the secondary winding 42. The polarity of the output terminals of the rectifier 46 and of the opposite plates of the capacitance 48 is indicated by the plus and minus signs placed on the drawing. The positive terminal of the device AVC¹ is connected with the ground electrode 44 over wires 50 and 49 and thence through the master volume control device MVC, while the negative terminal is connected over wire 53 with the grid leak of the tube 40 which includes the two resistors 51 and 52 in series. It is clear that by proper proportioning of the parts the gain of the amplifier HFA¹ will be automatically adjusted through the automatic volume control device AVC¹ in the same manner as pointed out hereinbefore in describing the control of the

device AVC over the gain of the amplifier HFA. It will be noted that the negative terminal of the device AVC¹ will be connected with the grid circuits of the tubes for the stages ahead of the 5 tube 49 by means of the wire 54.

It is to be seen, therefore, that the portion of the telephone current picked up from the channel including the traffic rails, and that the portion picked up from the channel including the 10 line wire 2 are individually filtered, amplified and demodulated and the corresponding audio frequencies are combined at the transformer T³, since the outputs of the two demodulators are supplied to the two primary windings 25 and 57 15 of the transformer T³ each of which will be effective to induce an electromotive force in the secondary winding 26 of that transformer. A portion of the output of each of the high frequency amplifiers is utilized through an associated 20 volume control device for adjusting the gain of the respective amplifier.

The audio or low frequency electromotive force induced in the secondary winding 26 of the transformer T³ as a result of the different currents supplied to the two primary windings 25 and 57 25 is utilized for operating a signaling device, in this instance the current being first further amplified at the electron tube 27. The amplifying tube 27 is preferably a pentode having a heated 30 filament 58, a plate 59 and two control grids 60 and 61 as well as a cathode screen grid for screening the secondary emission from the plate. The control grid 60 is provided with a circuit which includes the secondary winding 26 of the transformer T³, and the plate 59 is provided with a circuit which includes a battery 62 and the primary winding 63 of a transformer T⁵. The grid 61 is connected with the terminal of the primary winding 63 remote from the plate through 35 a resistor 64 across which is preferably connected two condensers 65 and 66 in series with a ground electrode 67 connecting at the mid-terminal of the condensers. It is clear that the electromotive force induced in the secondary winding 26 40 of the transformer T³ will be reproduced in the primary winding 63 of the transformer T⁵ greatly increased in amplitude which will, in turn, induce electromotive forces of like frequencies in the secondary windings 68 and 69 of the transformer T⁵. The energy supplied to the secondary winding 45 50 55 68 is delivered to the operating winding of a loud-speaker LS and hence the audio frequencies induced in the secondary winding 26 of the transformer T³ will be reproduced at the loud-speaker LS.

The portion of the output of the audio amplifier 27 supplied to the secondary winding 69 of the transformer T⁵ is applied to the input terminals of a full-wave rectifier 70 included in the master 60 volume control device MVC, the output terminals of the rectifier 70 being connected across a resistor 71 and a capacitance 72 in parallel. The polarity of the output terminals of the rectifier 70 is indicated by the plus and minus signs. 65 Consequently, the electromotive force induced in the secondary winding 69 is rectified and the capacitance 72 is charged at a potential substantially equal to the peak value of such electromotive force. The positive terminal of the master 70 volume control device MVC is connected with the ground electrode 44 over wire 73, while its negative terminal is connected with the wires 49 and 50 leading to the positive terminals of the automatic volume control devices AVC and AVC¹, 75 respectively, as traced hereinbefore. It is to be

noted that the connection of the devices AVC and AVC¹ with the ground electrode 44 includes the different arms of the rectifier 70 in the low resistance direction of the asymmetric units and the resistor 71 with the result that little resistance 5 is interposed by the master volume control device in the ground connection for the automatic volume control devices AVC and AVC¹. It is to be seen that the potential established for the capacitance 72 of the master volume control device MVC 10 will operate in series with the charge established on the capacitances 30 and 48 of the automatic volume control devices AVC and AVC¹, respectively, to adjust the negative grid bias of the respective amplifier, the potential of the capacitance 72 being effective to vary the grid bias of each of the high frequency amplifiers HFA and HFA¹ simultaneously and by equal amounts. That is, a portion of the output of the audio frequency amplifier is utilized for simultaneously 20 adjusting the gain of the two high frequency amplifiers. The parts of this master volume control device MVC are so proportioned that when the output of the audio amplifier 27 reaches a level that the response of the loud-speaker becomes too great, the gain of the high frequency amplifiers is reduced and the energy for operating the loud-speaker adjusted to a more desirable level.

In describing the operation of my invention I shall first assume that a non-transmitting period exists. Under this condition, whatever noise current is picked up from the traffic rails or from the line wires and passed to the respective high frequency amplifiers, the associated automatic volume control devices will be effective to adjust the gain of each amplifier accordingly, so that substantially an equal amount of noise is applied to each demodulating device. For instance, if the amount of noise received from the channel including the line wires is only one thousandth of the amount of noise received from the channel including the traffic rails, the high frequency amplifier HFA¹ will have its sensitivity automatically adjusted to a relatively high gain while the amplifier HFA will have its sensitivity adjusted at a relatively low gain, and the resultant noise currents applied to the input of the demodulators DM¹ and DM will be of substantially equal levels. In other words, due to the high level of noise in the traffic rail channel, the channel including the line wires is automatically made the preferred channel for receiving a signal by the amplifier HFA¹ being adjusted at high sensitivity and the amplifier HFA being adjusted at low sensitivity. 40 45 50 55 60 65 Should the noise received from the line wire channel be great and that received from the traffic rail channel low then the track channel is automatically made the preferred channel for receiving the signal by the amplifier HFA being adjusted at high sensitivity and the amplifier HFA¹ adjusted at low sensitivity. It is apparent, therefore, that the more desirable channel for receiving a signal is automatically selected during the non-transmitting period.

When a conversation is begun and the carrier current modulated by the voice frequencies is supplied to the traffic rails at the sending location, the receiver 3-4 and the receiver 37 will each pick up some electromotive force corresponding to the telephone current which is being transmitted. If the telephone current picked up by the receiver 37 is several times as great as the noise it is receiving, satisfactory communication can be carried out over the line wire channel 70 75 80 85 90 95

notwithstanding the noise level of the traffic rail channel may be relatively high. The energy corresponding to the voice frequencies picked up from the line wire channel will be filtered, amplified and demodulated independent of that picked up from the traffic rails. The telephone current picked up from the traffic rails will also be filtered, amplified and demodulated but, as we are now assuming that the rail channel is noisy, 5 the rail current will be amplified at low gain with the result that, when the two currents are combined after demodulation, the portion corresponding to the line wire current will greatly predominate and the combination will contain a 10 relatively low noise energy. After the two audio frequency currents are combined, the combination will be further amplified and applied to the loud-speaker LS where the telephone message will be reproduced. The master volume control device MVC will adjust the sensitivity of both the 15 high frequency amplifiers so that if the energy level of the combined telephone current as applied to the loud-speaker is higher than necessary for desirable operation their gain will be decreased 20 and the noise will still further fade into the background. The capacitance 12 and resistor 71 of the master volume control device MVC are so proportioned that relatively rapid action in both increasing and decreasing the sensitivity of the 25 high frequency amplifiers obtains and, hence, the desired amount of energy for desirable operation of the loud-speaker at all times is assured. It is 30 obvious that if the signal to noise ratio as received from the traffic rail channel is better than that of the line wire channel then the rail channel will be made the preferred channel for communication. Furthermore, if both channels are 35 relatively free from noise and sufficient energy for communication is received over each, the master volume control device will operate to desensitize 40 each high frequency amplifier to a point where the voltage of the combined audio frequencies is at a level for desirable operation of the loud-speaker.

45 It may happen that the telephone voltage received from the two channels will be equally good but out of phase. Such a condition will not seriously affect the operation of the loud-speaker because the difference in phase will be a relationship existing between the carrier or side-band 50 frequencies which are materially higher than the audio frequencies that operate the loud-speaker. Should the telephone voltages picked up from the two channels be out of phase as much as 180° 55 there will be no cancellation since each will be individually amplified and demodulated. After demodulation, addition of the two voice frequencies will not be seriously affected since the phase relationship of the relatively low voice frequencies compared with the 8000 cycle carrier 60 will not be over 45° out of phase at most. Thus, if the currents picked up from the different channels are considerably out of phase, they will still be near enough in phase to add with little 65 loss at the audio frequency amplifier where they are combined. That is to say, that by individually amplifying and demodulating the currents as received from the two different channels and then combining the resultant audio frequency 70 currents phase displacement of the two carrier currents will not seriously affect the final telephone current as applied to the loud-speaker.

75 Although I have here described a particular adaptation for receiving apparatus embodying my invention, it will be understood that I do not

wish to limit myself to telephone systems for railway trains, and receiving apparatus embodying my invention is equally useful for other communication systems wherein a signal current is received over two partially independent channels. 5 The application here shown will serve to illustrate the many places apparatus embodying my invention may be employed.

Although I have herein shown and described only one form of apparatus embodying my invention, it is understood that various changes and modifications may be made therein within the scope of the appended claims without departing from the spirit and scope of my invention. 10

Having thus described my invention, what I 15 claim is:

1. Receiving apparatus for communication systems having two channels over either one or both of which a carrier current modulated with voice frequencies flows comprising, a first and a second 20 receiver each coupled to a distinctive one of said channels, a first and a second amplifier each including an electron tube, means for connecting each receiver with the grid of a distinctive one of said tubes for individually amplifying the voltage picked up from said channels, an automatic 25 volume control device for each amplifier each including a rectifier having its input terminals connected with the plate circuit of the associated tube and a capacitance connected across 30 the output terminals of the rectifier and said capacitance having its high potential plate grounded and its low potential plate connected with the grid of the tube for adjusting the gain of the amplifier according to the magnitude of 35 the voltage picked up from the associated channel, a first and a second demodulator, means for connecting the input circuit of each demodulator with the output circuit of a distinctive one of 40 said amplifiers for individually demodulating the carrier telephone voltages received from said channels, a third amplifier including an electron tube, means for coupling the grid circuit of said last mentioned tube with the output of both of 45 said demodulators for amplifying the combined audio frequency currents, a loud-speaker coupled with the plate circuit of said last mentioned tube for reproducing the audio frequencies, and a third volume control device including a rectifier having its input terminals connected with the 50 plate circuit of the tube of said third amplifier and a capacitance connected across the output terminals of the rectifier and said capacitance having its high potential plate grounded and its low potential plate connected with the grids of 55 the tubes of said first and second amplifiers in parallel for adjusting the gain of both of said first and second amplifiers simultaneously in accordance with the magnitude of the combined 60 audio frequency currents. 60

2. Receiving apparatus for communication systems in which a telephone carrier current is supplied to a communication channel comprising, a receiver coupled with said channel for picking up such current, a high frequency amplifier including an electron tube, means for connecting the grid circuit of said tube with said receiver, a demodulator, means for connecting the input of the demodulator with the plate circuit of said tube, an audio frequency amplifier including an 70 electron tube, means for connecting the grid circuit of said last mentioned tube with the output of the demodulator, a telephone receiver connected with the plate circuit of said last mentioned tube, a first volume control device includ- 75

ing a rectifier and a capacitance and said device having its input terminals connected with the plate circuit of the high frequency amplifier tube and its output terminals connected with the grid 5 of said tube for adjusting the sensitivity of the tube according to the magnitude of the current picked up from said channel, and a second volume control device including a rectifier and a capacitance and said device having its input terminals connected with the plate circuit of the 10 audio frequency amplifier tube and its output terminals connected with the grid of the high frequency amplifier tube serially with the first volume control device for adjusting the sensitivity 15 of said high frequency amplifier tube according to the magnitude of the current supplied to said telephone receiver.

3. Receiving apparatus for communication systems in which a modulated carrier current is supplied to a communication channel comprising, a receiver coupled with said channel for picking up such current, a high frequency amplifier including an electron tube, means for connecting the grid circuit of said tube with said receiver, 20 a demodulator, means for connecting the input of the demodulator with the plate circuit of said tube, a low frequency amplifier including an electron tube, means for connecting the grid circuit of said last mentioned tube with the output 25 circuit of said demodulator, a signaling device connected with the plate circuit of said last mentioned tube responsive to the modulating frequency of the carrier, a first volume control device coupled with the plate circuit of the high frequency 30 amplifier tube and having connection with the grid of said tube for adjusting the grid bias voltage of the tube according to the magnitude of the current supplied to the demodulator, and a second volume control device coupled with the plate 35 circuit of the low frequency amplifier tube and having connection with the grid of the high frequency amplifier tube serially with said first volume control device for adjusting the grid bias voltage of that tube according to the magnitude 40 of the current supplied to said signaling device. 45

4. Receiving apparatus for communication systems for railway trains in which a carrier telephone current flows partly in the traffic rails and partly in a line wire paralleling said rails comprising, a first and a second receiver on a train 50 coupled with the rails and with said line wire respectively, a first and a second high frequency amplifier each including an electron tube, means for coupling the grid circuit of each tube with a particular one of said receivers, a first and a second demodulator, means for coupling the input circuit of each demodulator with the plate circuit of the tube of a particular one of said amplifiers, an audio frequency amplifier including 55 an electron tube, means for coupling the grid circuit of an audio frequency amplifier tube with the output circuits of both of said demodulators, a loud-speaker coupled with the plate circuit of said audio amplifier tube, a first and a second volume control device each including a rectifier, means for coupling the input terminals of each rectifier with the plate circuit of a particular one of the high frequency amplifiers and the output terminals of each rectifier with the grid circuit of the same high frequency amplifier tube, a master volume control device including a rectifier, and means for coupling the input terminals of the last mentioned rectifier with the plate circuit of the audio frequency amplifier tube 70 and its output terminals with the grid circuits of

the two high frequency amplifier tubes in parallel.

5. Receiving apparatus for communication systems for railway trains in which a carrier telephone current flows partly in the traffic rails and partly in a line wire paralleling said rails comprising, a first and a second receiver on a train coupled with the rails and with said line wire respectively, a first and a second high frequency amplifier each including an electron tube, means for coupling the grid circuit of each tube with a particular one of said receivers, a first and a second demodulator, means for coupling the input circuit of each demodulator with the plate circuit of a particular one of said amplifiers, an audio frequency amplifier including an electron tube, means for coupling the grid circuit of the audio frequency amplifier tube with the output circuits of both of said demodulators, a loud-speaker coupled with the plate circuit of said audio amplifier tube, a first and a second volume control device each coupled with the plate circuit of a particular one of the high frequency amplifier tubes and each having connection with the grid of the respective tube for adjusting the grid bias voltage of the tube according to the magnitude of the current supplied to the associated demodulator, and a master volume control device coupled with the plate circuit of the low frequency amplifier tube and having connection with the grid of each of the high frequency amplifier tubes for adjusting the grid bias voltage of those tubes according to the magnitude of the current supplied to the loud-speaker.

6. Receiving apparatus for communication systems for railway trains having a periodic signaling current which flows partly in the traffic rails and partly in a line wire paralleling the rails comprising, a first and a second receiver on a train coupled with the traffic rails and with said line wire respectively, said first receiver mounted on the train for effective inductive relationship to the rails and substantially non-inductive relationship to the line wire and said second receiver mounted for effective inductive relationship to the line wire and substantially non-inductive relationship to the rails, a first and a second amplifier, means for connecting the input circuits of said amplifiers with said first and second receiver respectively, a first and a second detector, means for connecting the input circuits of said detectors with the output circuits of said first and second amplifiers respectively, means coupled with the output circuits of both of said detectors for combining the currents picked up from the traffic rails and from said line wire after detection, and signaling means controlled by the last mentioned means responsive to such signaling current.

7. In railway train communication systems wherein a modulated carrier current flows partly in each of two channels one of which includes the traffic rails and the other of which includes a line conductor extending along the track receiving apparatus comprising, a first inductor having portions mounted on a train directly over each of the rails for inductively receiving energy due to such current flowing in said one channel, a second inductor mounted relatively high on the train in inductive relation with said conductor for inductively receiving energy due to such current flowing in said other channel, train carried amplifier-demodulator means having connections with said first and second inductors for receiving and combining the energy picked up from both

of said channels, said amplifier-demodulator means operative to combine the energy picked up from the two channels after demodulation to avoid loss in effectiveness due to phase difference of the currents flowing in said channels, and signaling means connected with the output of said amplifier-demodulator means responsive to such combined energy.

8. In railway train communication systems
10 wherein a modulated carrier current flows partly in each of two channels one of which includes the traffic rails and the other of which includes a line conductor receiving apparatus comprising, a first and a second inductor mounted on a train
15 for inductive relationship with the conductor and the traffic rails respectively, said first inductor mounted relatively high and in a vertical plane on

the train and said second inductor mounted on the train in a horizontal plane with portion over each rail, amplifier-demodulator means on the train having connections with said inductors for combining the energy picked up from said channels, said amplifier-demodulator means operative to combine the energy after demodulation to avoid loss in effectiveness due to phase difference in the currents flowing in said channels, means connected with the output of said amplifier-demodulator means for automatically adjusting said amplifier-demodulator to give preference to one or the other of said channels, and signaling means connected with the output of said amplifier-demodulator means responsive to the combined energy.

WILLARD P. PLACE.
